UNITED STATES PATENT OFFICE.

CYRUS S. WERT, OF KENDALLVILLE, INDIANA.

METHOD OF FORMING FACED CONCRETE BLOCKS.

Application filed August 31, 1921. Serial No. 497,142.

To all whom it may concern:

Be it known that I, CYRUS S. WERT, residing at Kendallville, in the county of Noble and State of Indiana, a citizen of the United States, have invented certain new and useful Improvements in Methods of Forming Faced Concrete Blocks, of which the following is a specification, reference being had to the accompanying drawings, forming a part hereof.

My invention relates to a method of forming concrete blocks for building or other purposes with a facing different in quality from the main body of the block, and my invention has for its object to produce a concrete block having a facing which will be waterproof and durable and will not crack off or separate from the body of the block by the action of the frost or other weather action and which will effectively protect the body of the block from the action of frost or other weather action and will prevent the defacement of the block by the working out of any excess of lime which may be present in the body of the block.

With the above described objects, and other objects hereinafter explained, in view, my invention consists in the method herein-after described and claimed.

Referring to the drawings which show a simple form of apparatus adapted for carrying out my invention and which are illustrative only and are not intended to in any way limit or restrict the invention to the use of the apparatus shown or to any particular apparatus,

Figure 1 is a cross sectional view of a mold and tamper for forming a concrete block showing the portion of the mold back of the dividing plate filled and ready to receive the facing mixture.

Fig. 2 is a view of the mold after the space in front of the dividing plate has been filled with the facing mixture.

Fig. 3 is a similar view showing the front facing in position after the dividing plate has been removed and the block tamped.

Fig. 4 is a similar view showing the block with its upper surface removed ready to receive the top facing.

Fig. 5 is a similar view showing the completed block with the tamper in position to force the top facing into intimate contact with the main portion and front facing of the block, and

Fig. 6 is a view of a form of scraper which may be used in removing the top of the main portion of the block.

In the drawings 1 indicates the front plate, 2 the bottom plate and 3 the back plate of a mold adapted to receive concrete to form a block. 4 indicates a tamper carried by an arm 5 and adapted to be brought down on to the mass of concrete in the mold to compress and solidify it and force it against the walls of the mold. 6 indicates a spacing plate adapted to fit within the mold near the front plate 1. 7 indicates a scraping bar adapted to be used to remove the top portion of the block formed in the mold, having the serrated edge 8. 9 indicates a removable hopper adapted to be placed on top of the mold to direct the concrete into the mold and to hold such additional amount of the concrete as may be necessary to fill the mold when the tamper is applied.

In carrying out my method I place in the mold as shown near its front plate 1, preferably about one-fourth inch from it, the spacing plate 6, this spacing plate being preferably about one-fourth inch in thickness, and fill the main portion of the mold, back of the spacing plate with the usual wet concrete mixture of sand, or sand and gravel, and cement in the proportions commonly used, wet enough to pour, preferably using to wet the concrete and aggregate water containing as much hydrate of lime as will dissolve in it or even containing more or less hydrate of lime in suspension, and fill the space between the spacing plate and the front plate of the mold with the facing composition.

The spacing plate is then drawn out, leaving a space of about one-fourth inch between the front face of the main portion of the block and the facing material introduced between the facing plate and the front plate of the mold, which is at once filled by the flowing together of the material forming the main portion of the block and material forming the facing. The facing composition used

preferably consists of equal parts of cement, fine sand and finely divided marble or limestone, wet up to form concrete, with water containing as much hydrate of lime as it will dissolve, and water glass in the proportion of about one pint of the ordinary commercial water glass to five gallons of the lime water.

Coloring matter, preferably

in powdered form, may be added to the concrete thus formed. The facing and the material forming the main portion of the block are then forced into intimate union and the 5 block solidified by tamping.

As soon as the facing space is thus filled, the facing plate removed and the block tamped, the hopper 9 is removed and the top 10 surface of the block formed is removed to a depth preferably of about one-fourth inch, in such a way or by the use of such an instrument as to leave the top of the block rough or serrated, as by the scraper 7 having the serrated edge 8. The rough or serrated 15 surface thus formed is then wetted with the lime water containing water glass, above described, and the hopper 9 being replaced, the facing concrete mixture is poured over the block to the desired depth and this 20 layer of facing material is then tamped. This tamping, which is an important step in the method, forces the facing material into the cavities formed in the top of the main portion of the block and also in the 25 front facing and effects a thorough union of the top facing with these other portions of the block.

All of the steps of the method described are carried out before the portion of the 30 block first formed begins to set more than just sufficient to retain its shape and not sufficient to form a surface to which the facing material will not readily adhere, particularly when wetted as described.

35 The facing mixture of fine sand, marble or limestone dust and cement would form of itself, a substantially water-proof facing mixed with water not containing hydrate of lime or water glass, but the addition of the 40 lime adds to the strength of the cement and the water glass acts to close the pores against the passage of moisture either inward or outward and thus prevents any excess of lime which may be contained in the 45 concrete from working out to the surface to cause the whitish appearance often observable on concrete blocks exposed to the weather.

When the faced block has been thus formed 50 and before it is removed from the mold it is watered with the water containing hydrate of lime and water glass in solution and, during the curing of the block after it is removed from the mold, this watering with 55 the same solution is repeated at intervals.

When the faced block formed as above described has become thoroughly cured the line of contact between the facing and the body of the block will not form a line of cleavage, the block if forcibly broken tending to break 60 otherwise than on this line and the expansion and contraction of the block by changes in temperature will not tend to cause cleavage along this line of contact.

The inner face of the front plate of the

mold and the bottom face of the tamper may, if desired, be formed other than plain so as to give the facing any ornamental appearance desired such as that commonly termed tapestry.

70

While the apparatus shown is particularly adapted for forming so-called concrete bricks, that is solid blocks having the size and shape of the ordinary clay brick, the molds may be of other shapes or sizes and 75 may be constructed to form hollow blocks as well as solid blocks.

The concrete mixture for the facing and preferably also that for the main portion of the block should be sufficiently wet to permit 80 of its being poured.

If it is desired to face only one of the faces of the block, the dividing plate may be dispensed with, the main portion of the block being made of the full size of the 85 mold, its top surface being removed and the facing poured on and tamped as described.

A small proportion of hydrate of lime is 90 preferably mixed with the cement and marble dust to form the facing mixture.

90

The hydrate of lime and water glass may be omitted from the water used to wet up the facing mixture but it is found convenient in making the concrete blocks to prepare a considerable quantity of the hydrate 95 of lime and water glass solution and to use this solution in making the concrete mixture for the main portion of the block as well as for the facing mixture and the other purposes described, the use of this solution in 100 wetting the block before removing it from the mold and during the curing being particularly important.

100

Having thus described my invention, what I claim is:

105

1. The method of forming concrete blocks having a face provided with facing material distinct from the material of the main portion of the block, which consists in first forming the main portion of the block, removing the top surface of said main portion of the block before it has become fully set, wetting the top surface left on the main portion of the block with lime water containing water glass in solution, applying the facing mixture to the wetted surface, and tamping said facing mixture into intimate union with said main portion of the block.

115

2. The method of forming concrete blocks having two faces provided with facing material distinct from the material of the main portion of the block, which consists in placing a dividing plate near one face of a mold, filling the mold back of the dividing plate with concrete mixture, filling the space 120 between the dividing plate and the adjacent face of the mold with the facing mixture, withdrawing the dividing plate to permit the facing and main portion of the block to flow together, tamping the block thus 125

125

130

formed, removing the top surface of the faced block thus formed in a manner to leave a rough surface, wetting said rough surface with lime water containing water glass in solution, applying the facing mixture to the top surface remaining on the block thus formed, and tamping the facing mixture so applied into intimate union with the main portion of the block and the facing first formed.

3. The method of forming concrete blocks having a face provided with facing material distinct from the material of the main portion of the block, which consists in first

forming the main portion of the block, removing the top surface of said main portion of the block before it has become fully set, applying the facing mixture in wet condition to the top surface left on the main portion of the block, tamping said facing mixture into intimate union with said main portion of the block, wetting the block so formed with water containing hydrate of lime and water glass in solution and permitting the block to cure.

In testimony whereof I hereunto affix my signature.

CYRUS S. WERT.
